UNITED STATES PATENT OFFICE

JOHN L. HALMAN, OF LOS ANGELES, CALIFORNIA

DESIGN FOR AN ELECTRIC GRIDDLE

Application filed December 31, 1930. Serial No. 38,156. Term of patent 14 years.

To all whom it may concern:

Be it known that I, JOHN L. HALMAN, a citizen of the United States, residing in Los Angeles, county of Los Angeles, and State of California, have invented a new, original, and ornamental Design for Electric Griddle, of which the following is a specification, reference being had to the accompanying drawing, forming a part thereof.

Fig. 1 is a perspective view of the electric griddle, showing my new design, and Fig. 2 is an end view thereof.

I claim:

The ornamental design for an electric griddle substantially as shown.

JOHN L. HALMAN.
